(57) **CLAIM**

The ornamental design for a storage cabinet for food ingredient, as shown and described.

DESCRIPTION

1. Storage cabinet for food ingredient

1.1 : Perspective

1.2 : Front

1.3 : Back

1.4 : Left

1.5 : Right

1.6 : Top

1.7 : Bottom

The broken lines depict portions of the storage cabinet for food ingredient that form no part of the claimed design. The oblique shading lines denote a transparent surface. The grey tint in Figure 1.2 depicts a portion of the storage cabinet for food ingredient that forms no part of the claimed design.

1 Claim, 7 Drawing Sheets(56)
